UNITED STATES PATENT OFFICE.

CHARLES CECIL BERESFORD WHYTE, OF HATLEY MANOR, CARRICK-ON-SHANNON, COUNTY OF LEITRIM, IRELAND.

SAFETY-HOLDER FOR FIRE-ARMS.

SPECIFICATION forming part of Letters Patent No. 393,677, dated November 27, 1888.

Application filed September 11, 1888. Serial No 285,135. (No model.) Patented in England July 23, 1888, No. 10,651.

To all whom it may concern:

Be it known that I, CHARLES CECIL BERESFORD WHYTE, a subject of the Queen of Great Britain, residing at Hatley Manor, Carrick-on-Shannon, in the county of Leitrim, Ireland, have invented a new and useful Safety-Holder for Fire-Arms, (for which I have made application for a patent in Great Britain, which patent when granted will bear date July 23, 1888, No. 10,651,) of which the following is a specification.

My invention relates to a holder for a fire-arm—such as a revolver, carbine, or the like—so constructed that it retains the weapon firmly, preventing its accidental discharge while so held, and that it permits the arm to be detached by a single movement of the hand, which in effecting that action holds the weapon ready for use.

20 I will describe a holder according to my invention for a revolver or pistol, referring to the accompanying drawings.

Figure 1 is a front view showing the holder retaining a revolver, and Fig. 2 is a section.

25 The holder A is a bent steel spring, which may hang from a belt, B, as shown, or may be attached to the dress of a wearer near his left side, so as to present the stock of the weapon conveniently to his right hand.

30 To the front limb of the holder A is fixed a boss, C, projecting inwardly toward the back limb, but terminating with a rounded end at a little distance from the back limb. This boss may be of hard wood or such like material, secured to the front limb by a rivet, or it may be, as shown, a metal thimble made hollow for the sake of lightness, secured by riveting or brazing to the front limb. The wearer, taking hold of the weapon by its stock, inclines 35 it in such a way that he can insert the trigger-

guard D edgewise between the boss C and the back limb of the holder. When the trigger-guard has passed the boss, the weapon being let go hangs in the position shown in Fig. 1, the trigger guard resting on the boss C. As 45 this boss occupies nearly all the space behind the trigger between it and the hinder limb of the trigger-guard, the trigger cannot be pulled back while the weapon is retained in the holder, and consequently there can be no accidental discharge while the weapon is so held. When it is required for use, the wearer has only to take hold of the stock of the weapon and by a smart partial turn and downward strain he causes the trigger-guard to 55 pass the boss C edgewise, thus releasing the weapon which he has in his hand ready for use.

Obviously a holder such as I have described, instead of being attached to a belt or garment 60 worn on the person, might be attached to a saddle.

Having thus described the nature of my invention and the best means I know for carrying the same into practical effect, I claim— 65

A safety-holder for a fire-arm, consisting of a U-shaped spring, A, having a boss, C, attached to one limb projecting in toward the other limb and adapted to engage the trigger-guard of a fire arm, said boss terminating in 70 a spherical end, substantially as shown and described.

In testimony whereof I have signed my name to this specification, in the presence of two subscribing witnesses, this 23d day of August, A. 75 D. 1888.

CHARLES CECIL BERESFORD WHYTE.
